UNITED STATES PATENT OFFICE

OTTO STARKE, OF BERLIN, GERMANY

DRAFT-REGULATING MEANS

Application filed July 8, 1930, Serial No. 466,518, and in Germany July 9, 1929.

The present invention relates to dampers for regulating or checking the draft in the flues of stoves, furnaces, etc., and it is the object of the present invention to generally improve on contrivances of this kind.

Draft-regulating means have already been proposed, in which the damper or slide member forms in the closed position together with the frame a passage for the air which, upon 10 the closing movement, is caused to communicate with the atmosphere, and through which, in the case of leakage or untight closure along the bearing faces of the damper, air is sucked up from the atmosphere by reason of the draft 15 prevailing in the chimney. These dampers, however, are accompanied by the disadvantage that the same form the air passage only on a part of the periphery of the flue, so that 20 on the remaining part of the periphery the damper does not perform a sufficiently tight closure.

To overcome this disadvantage there is provided, according to the invention, a hollow damper frame, which extends over the whole 25 periphery of the cross-section of the flue, and which is open on the side directed towards the damper plate and is pressed against the same upon the closing movement by means of pressure rollers moving over wedge-like elevations 30 thereon, while the hollow damper frame communicates with the atmosphere through the medium of a pipe, the closure flap of which, when the slide is open, is opened in positive fashion by the smoke slide upon its 35 closing movement.

This arrangement has the advantage that the smoke slide according to the invention may be used alone, and with the same a greatly improved effect is obtainable as compared 40 with the arrangements hitherto usual. Alternatively, the new form of slide may be provided as a secondary slide behind an ordinary slide member, and in this case provides a much better closure of the flue than two ordinary slides having an opening for the air 45 in front of or behind the second ordinary slide.

The invention will now be described more 50 fully with reference to the accompanying

drawings, which illustrate a possible form of embodiment by way of example.

Fig. 1 shows the new slide in its application to a boiler flue.

Fig. 2 is a section through the flue, showing 55 the slide, according to the line 2—2 in Fig. 3.

Fig. 3 is a section according to the line 3—3 in Fig. 2,

Fig. 4 a section along the line 4—4 in Fig. 2, and

Fig. 5 an enlarged view of the air inlet pipe.

Referring now to the drawings, the damper 11 (Fig. 1) is fitted in the usual manner in the flue 12 between the boiler 13 and the chimney 14, and is connected by means of the rope or cable 15 over rollers or pulleys 16 with a counterweight 17.

In the flue 12, as shown in Figs. 2—4, there is provided for the damper or slide 11 a guide and sealing frame 18, against which the 70 slide 11 is so moved with the usual play between ledges 19 and 20 that the same is capable of responding to expansion by reason of heat. The frame 18 possesses about the periphery a passage 21, which is open towards the damper or slide 11. The slot 22 in the top 23 of the flue 12 is covered by the sheet metal housing 24, into which the damper 75 passes in the open position, so that no false air is able to enter the flue.

The damper or slide 11 possesses on the one side a number of wedge-shaped elevations 25 which, when the slide 11 is closed, pass over rollers 26 mounted on eccentrically adjustable bolts 27 on the frame 18. In this manner the damper or slide 11 is in the closed position pressed firmly against the frame 18, so that any leakage between the slide 11 and the frame 18 is reduced to the lowest possible amount.

Since, however, the draft of the chimney is still able to exert a slight effect even on this minimized leakage, it is necessary to do away with the latter also. For this purpose there is connected to the passage 21 a pipe 28, which leads to the atmosphere, and at the upper end it is closed by means of a flap 29. This flap possesses a lever 30, to which there is pivoted a rod 31 guided at 95 32 against the pipe 28. The rod 31 is fur- 100

nished at the lower end with a hook 33, which is capable of being engaged by an abutment or by the screw head 34 of the slide 11.

When the slide is lowered the screw head 34, shortly before the closed position of the slide is reached, moves against the hook 33 and conjointly moves the rod 31, the flap 29 thus being opened. When, therefore, the damper or slide 11 is closed, air from the atmosphere is able to enter the passage 21 through the flap 29 and the pipe 28, so that the draft in the chimney is incapable of exerting any action on possible leakage between the frame 18 and damper 11, but sucks up air from the atmosphere.

Since the amounts of air sucked up by the chimney can only be very small, the air is preheated by the heat radiated by the boiler and the passages towards the damper, so that any appreciable cooling of the gas in the chimney is unable to occur even in the case of relatively long stationary periods.

Normally, the heat radiated by the boiler and the flue will increase the temperature of the damper, causing it to expand. The arrangement according to the invention is thus accompanied by the additional advantage that this heat, at least for the greater part, is discharged through the air way, or is compensated thereby respectively, so that a warping or distortion of the damper will not take place, while at the same time the air passage will freely permit of any expansion which the damper may nevertheless tend to undergo.

When the damper 11 is lifted, the wedge-shaped elevations 25 are released from the rollers 26, and the flap 29 is closed, so that atmospheric air is no longer able to enter the flue 12.

It will be understood that no restriction is made to the specific form of embodiment shown in the drawings, which is quoted merely by way of example, and that various modifications are quite possible within the meaning of the above and the annexed claims without departing from the spirit of the invention.

What I claim as new and desire to secure by Letters Patent is:

1. In a draft-regulating means for furnaces, stoves and the like, a flue, a damper in the said flue, a hollow damper frame extending over the whole periphery of the cross-section of the flue, an open passage in the said frame having the interrupted portion of its periphery directed towards the said damper, a pipe connecting the said passage with atmosphere, a closure flap to the said pipe, and means for positively opening the said flap upon the closing movement of the said damper.

2. In a draft-regulating means for furnaces, stoves and the like, a flue, a damper in the said flue, a hollow damper frame extend-

ing over the whole periphery of the cross-section of the flue, an open passage in the said frame having the interrupted portion of its periphery directed towards the said damper, a pipe connecting the said passage with atmosphere, means for tightly pressing the said damper against the said frame, a closure flap to the said pipe, and means for positively opening the said flap upon the closing movement of the said damper.

3. In a draft-regulating means for furnaces, stoves and the like, a flue, a damper in the said flue, a hollow damper frame extending over the whole periphery of the cross-section of the flue, an open passage in the said frame having the interrupted portion of its periphery directed towards the said damper, a pipe connecting the said passage with atmosphere, means for tightly pressing the said damper against the said frame, a closure flap to the said pipe, a lever on the said flap, a hooked rod pivoted to the said lever, and an abutment on the said damper adapted to engage with the hook of the said rod for the purpose of positively opening the said flap upon the closing movement of the said damper.

4. In a draft-regulating means for furnaces, stoves and the like, a flue, a damper in the said flue, a hollow damper frame extending over the whole periphery of the cross-section of the flue, an open passage in the said frame having the interrupted portion of its periphery directed towards the said damper, a pipe connecting the said passage with atmosphere, wedge-shaped elevations on the one face of the said damper, rolls on the said frame adapted to be engaged by the said elevations for tightly pressing the said damper against the said frame, a closure flap to the said pipe, and means for positively opening the said flap upon the closing movement of the said damper.

5. In a form of embodiment of a draft-regulating means for furnaces, stoves and the like, a flue, a damper in the said flue, a hollow damper frame extending over the whole periphery of the cross-section of the flue, an open passage in the said frame having the interrupted portion of its periphery directed towards the said damper, a pipe connecting the said passage with atmosphere, wedge-shaped elevations on the one face of the said damper, rolls on the said frame adapted to be engaged by the said elevations, a closure flap to the said pipe, a lever on the said flap, a hooked rod pivoted to the said lever, and an abutment on the said damper adapted to engage with the hook of the said rod.

In testimony whereof I have affixed my signature.

OTTO STARKE.
